S. F. CLARKSON

RECEIPT BOOK

Filed Apr. 26, 1920

Inventor
Stewart F. Clarkson
By *Paul H. Reed*
HIS ATTORNEYS

UNITED STATES PATENT OFFICE.

STEWART F. CLARKSON, OF ST. CHARLES, MINNESOTA.

RECEIPT BOOK.

Application filed April 26, 1920. Serial No. 376,603.

To all whom it may concern:

Be it known that I, STEWART F. CLARKSON, a citizen of the United States, and a resident of St. Charles, Winona County, Minnesota, have invented certain new and useful Improvements in Receipt Books, of which the following is a specification.

The object of my invention is to provide a book adapted particularly for use in creameries where a machine is used for entering data on a ticket indicating the amount of sweet or sour cream delivered and a corresponding entry is also made on the leaf of a book wherein the account of the person selling the cream to the creamery is kept, the ticket being removed and delivered to the seller as a receipt for the cream delivered.

The machine used for this purpose is the type known as the "railroad machine" where-
20 in provision is made for duplicating or re-
producing the printing of an item or data
and the use of the machine of course render-
ing it impossible for any mistakes to occur
through transposition of the figures or
25 an error in reproducing the figures on the
ticket or leaf.

The invention consists generally in various constructions and combinations, all as hereinafter described and particularly pointed
30 out in the claims.

In the accompanying drawings forming part of this specification,

Figure 1 is a perspective view of a book embodying my invention,

35 Figure 2 is an edge view of the same,

Figure 3 is a similar view, showing a modified means for securing the leaves of the book together.

In the drawing, 2 represents a leaf of the
40 book, having at one end a ticket 3 formed preferably by slitting the book transversely at 4 and then extending a line of perforations 5 from the end of the slit to the end of the book opposite its bound portion.
45 This ticket, which is folded over and torn out when the proper entry has been made thereon, constitutes a receipt to the farmer or other person delivering cream and, as indicated in Figure 1, the inner face of the
50 ticket has the wording "Sweet cream" and "Sour cream" thereon with blank spaces whereon the date and the number of pounds of cream may be entered. The ticket is preferably about half the width of the leaf
55 of the book so that space is provided on the leaf for a reproduction of the printing on

the ticket and this is done by means of the well-known machine that is adapted for printing a date and figures representing pounds and then by a simple manipulation 60 will repeat this printing on another part of the same leaf or sheet. This arrangement is shown plainly in Figure 1, where the words "Sweet cream" are printed at the end of the leaf with a blank space beneath 65 for the number of pounds of cream delivered on the 8th of April. Under the heading "Sour cream" provision is made for printing similar figures representing the date and the weight of the cream. When this 70 printing is completed, the ticket is folded on the line of perforations and torn out and given to the farmer or seller of the cream, while the creamery retains the book and uses the memorandum thereon as an 75 open account with the seller of the cream, and a clerk can, at any time by the use of an ordinary adding machine, easily and quickly ascertain the number of pounds delivered in a certain time.

For convenience of inserting the leaves in the machine, the printing is done on the inner face and to allow for convenient movement of the leaves the book is preferably bound by means of the loops or links 6. 80 These, as shown in Figure 2, are preferably oval in form and made of wire, suitable holes being provided in the leaves through which the loops are inserted.

In Figure 3 a cord 7 is substituted for 90 the wire loops. In other respects the book is the same as described with reference to the other figures.

I claim as my invention:

1. A receipt book comprising leaves held 95 together at one end, said leaves having slits therein extending transversely from one edge to a point near the center and also having a line of perforations extending from the inner end of the slit to the unbound end of 100 the leaf, said ticket and the adjacent face of the leaf having appropriately designated blanks for the day of the month and the number of pounds of the article delivered, duplicate entries being made on the face of 105 the ticket and on the leaf, the tickets when removed and delivered to the seller becoming a receipt when the transaction is completed, the leaf being retained by the purchaser and forming a permanent record of the sale. 110

2. A receipt book comprising leaves and loops for loosely binding the leaves together

at one end, the opposite end of the leaf having separating lines extending longitudinally and transversely therein and intersecting to form a detachable ticket at one edge of the leaf, one face of said ticket and the adjacent corresponding face of the leaf having duplicate entries made thereon as a record of the sale, the ticket being delivered to the seller and the leaf forming a permanent record of

the transaction and the account with the seller.

In witness whereof, I have hereunto set my hand this 21st day of April, 1920.

STEWART F. CLARKSON.

Witnesses:

W. E. SPENCER,
GEO. ECKLES.
